UNITED STATES PATENT OFFICE.

ALFRED ERNST, OF PITTSBURGH, PENNSYLVANIA.

GAS-CLEANER.

1,062,446.

Specification of Letters Patent. Patented May 20, 1913.

Application filed December 13, 1912. Serial No. 736,597.

To all whom it may concern:

Be it known that I, ALFRED ERNST, a citizen of the United States, resident of Pittsburgh, in the county of Allegheny and State of Pennsylvania, have made a certain new and useful Invention in Gas-Cleaners; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a central vertical section of the invention. Fig. 2 is a similar view of a modification.

The invention relates to apparatus for cleaning gas, and particularly gas liberated in gas producers from bituminous coal; and it consists in the novel construction and combinations of parts, as hereinafter set forth.

In the accompanying drawings, illustrating the invention in an apparatus of preferable form, the numeral 2, indicates a casing, the upper portion 3, of which is preferably of cylindrical form, and is provided with a central recess 4, the bottom of which is in the form of an annular water-seal cup 5; around a central opening 6. To the top of this portion is attached the outlet pipe 7. The chamber in this portion disposed around the recess 4 is annular, and is provided with perforated racks 8, for the reception of drying material designed to absorb moisture from the gas after being washed. To this upper portion is connected the main lower portion of the casing, extending downward and provided at its bottom with a water-holding connection 9, which is preferably a water-seal tank or basin having an overflow pipe at 10. In the casing are provided an upper chamber 11, for a centrifugal water distributing device, and a lower entrance chamber 12, which extends below the water level and to which the entrance pipe or inlet 13, is connected. The wall of a tubular throat or partition passage 14, extends centrally upward into the upper chamber 11, and downward from the upper chamber through the lower chamber, separates these chambers and is terminated at or slightly below the overflow level by a horizontal series of notches or passages 15, through which the

crude gas is designed to pass from the entrance chamber, into this throat or passage and upward into the main cleansing chamber. A drain passage 16, which may be circumferential, extends downward from the sloping floor of the upper chamber into the water holding basin. This throat or partition passage is therefore designed to provide communication between the entrance chamber and the washing chamber only through the water of the tank.

Through the central opening 6, of the top of the casing extends a shaft 17, the upper portion of which is water-sealed in the cup 5, above which it is provided with a pulley or other means of communicating motion. The lower end portion of the shaft extends into the interior vertical tubular passage 14, and is provided with blades 18. The middle portion of the shaft is provided with fan blades 19, and, below these, with a rotary inverted cup device, the skirt or wall of which extends downward around the upper part of the tubular passage 14. This skirt or wall is provided with exterior ledges 20, which may be and usually are of bracket-form and horizontal or inclined; and opposite this wall the casing wall is provided with flanges 21, which are inclined. The casing flanges are arranged at levels between the cup ledges, and, as the casing wall and cup wall are designed to be parallel, or nearly so, the annular deflecting passage between them is arranged to distribute the gas and water particles in an even manner.

A water supply is provided in the upper part of the casing, as indicated by the jets at 22. And water spouting devices 29 are shown in the chamber 12, near the water level and preferably directed toward the passages or serrations 15, these being designed to wash away the tar and soot which tends to float and accumulate in the water of the entrance chamber around these passages.

In the operation of the apparatus, the crude gas from the producer, entering the lower chamber 12, is drawn over the surface of the water inward through the horizontal series of notches or passages of the tubular wall in separate streams, which are subdivided by the bubbling action into small portions, which, being brought into contact with the mass of water of the tank, are materially cooled. Also much of the heavier

soluble matter is taken from the gas. The gas, moving upward through the tubular passage 14, is deflected downward by the skirt wall of the inverted cup, and, at the same time, is given a whirling motion, which continues as it passes around the edge of this wall upward through the deflecting passage between the ledges of the cup wall and the flanges of the casing wall.

10 Meeting the falling spray, which is given centrifugal motion as it passes outward and inward between the flanges of the casing wall and the ledges of the cup wall, it is further washed and cooled, the soluble matters falling upon the sloping bottom of the upper chamber and being drained into the tank below through the circumferential drain passage of the casing. Below the drying chamber the wall and flanges of the casing

15 slope downward, and the cup wall has also a downward slope, and the ledges of the exterior of this wall are preferably arranged in staggered relation, or separated at intervals by vertical passages, it being designed to obviate the collection of heavy extractive in this part of the apparatus, and to facilitate its downward movement. The cleaned and moistened gas is carried to the outlet through the drying material on the

20 racks of the drying chamber, which is made sufficiently extensive to provide for a comparatively slow movement of the gas, and in this way to promote an effective drying action, so that the gas passing through the

25 30 35 outlet pipe will be in condition for use.

In some cases, in order to provide an abundant distribution of the water or cleaning fluid, supply spouts 23 may be arranged around the casing at different levels, to discharge the fluid toward or upon the shelves of the rotary inverted cup or deflector 25. In these cases, the casing ledges may be dispensed with, as the discharge from the spouts will cause lateral inward currents of

40 45 the gas.

I claim—

1. Apparatus for cleaning gas, comprising a casing having an entrance chamber and a washing chamber, a water holder at the bottom of said entrance chamber, an overflow for said water holder, an inverted deflecting cup within the washing chamber, and a tubular partition passage within the entrance chamber extending upward into said deflecting cup and downward into the water holder, said passage being provided with rotary blades above and passages at the water level for causing the gas to bubble through the water from the entrance chamber into the partition passage.

2. Apparatus for cleaning gas, comprising a casing having an entrance chamber and a washing chamber above said entrance chamber, a water holder at the bottom of said entrance chamber, an overflow for said wa-

ter holder, a rotary inverted deflecting cup within the washing chamber, and a partition passage extending upward into said deflecting cup and downward through the entrance chamber into the water holder, said passage being provided with a series of serrations at the water level to subdivide and direct the gas through the water from the entrance chamber into the partition passage.

3. Apparatus for cleaning gas, comprising a casing having a water holder at its bottom, an overflow discharge an entrance chamber extending into said water holder, a washing chamber above said entrance chamber a drying chamber above the washing chamber, a rotary inverted deflecting cup within the washing chamber, and a tubular partition passage between the entrance chamber and the washing chamber having a circumferential series of passages at the water level for the passage of the gas from the entrance chamber through the partition passage inward to the washing chamber.

4. Apparatus for cleaning gas, comprising an overflow water holder an entrance chamber extending downward into the water holder, a washing chamber above the entrance chamber, an inverted deflecting cup within the washing chamber, a water spray in said washing chamber, and a partition passage extending through the entrance chamber for communication between said entrance chamber and said washing chamber, said partition passage having openings at the water level rotary means to cause centrifugal movement of the spray, water, and means to cause the gas to pass through the water from the entrance chamber into the passage of communication.

5. Apparatus for cleaning gas, comprising an entrance chamber, a washing chamber above the entrance chamber, an upper drying chamber opening into the washing chamber, a bottom overflow water holder, an inverted deflecting cup within the washing chamber, a partition passage of communication extending upward under said deflecting cup and having a series of passages at the water level, and jet devices in the entrance chamber for keeping these passages clear.

6. Apparatus for cleaning gas, comprising a casing having an entrance chamber, a washing chamber interior flanges of said washing chamber, a rotary shaft, an inverted deflecting cup in said washing chamber on said shaft, exterior ledges of said cup, a fan device on said shaft, an overflow water holding tank at the bottom of the casing, a drying chamber at the top of the casing, and a partition passage separating the entrance chamber from the washing chamber to the water level and provided at the water level with means for the passage of the gas from the entrance chamber to the washing chamber.

7. Apparatus for cleaning gas, comprising an overflow water holder, an entrance chamber opening downward therein, a washing chamber above the entrance chamber, a central tubular passage extending from the washing chamber through the entrance chamber and having a series of passages at the water level, a deflecting cup around the upper end of the tubular passage, a rotary shaft extending into said tubular passage, and fan blades secured to said shaft.
8. Apparatus for cleaning gas, comprising an overflow water holder, a casing opening at bottom into said water holder, drying racks at the top of the casing, a washing
- chamber in the upper part of said casing, a tubular passage from the washing chamber downward into said water holder, an entrance chamber in the lower part of said casing surrounding said passage, an inverted 20 deflecting cup in the washing chamber and a rotary fan carrying said cup, and extending into said passage.
- In testimony whereof I affix my signature, in presence of two witnesses.
